UNITED STATES PATENT OFFICE

DAVID P. WOLHAUPTER AND EMORY L. GROFF, OF WASHINGTON, DISTRICT OF COLUMBIA

RAIL-JOINT BAR

Application filed January 17, 1930. Serial No. 421,564.

This invention relates to rail joint bars, and has in view to provide a rail joint bar embodying a novel combination of desirable features designed to provide an effective support for the rail ends and at the same time to minimize tendency of the bar to "kick out" under load, whereby wear on the bar and on the rail ends is minimized and longevity of the bar and the rails is assured.

10 In its broader aspects the invention contemplates the provision of a rail joint bar which is both headfree and footfree; that is, a bar which is inclusive of a head formed for loading engagement with the head fillet 55 of the rail and for clearance from the underside of the rail head, and a foot or base which is formed for loading engagement with the base fillet of the rail and for clearance from the upper face of the rail flange, whereby 60 the resultants of the load forces transmitted through the bar are directed inward with consequent tendency of the bar to move inward and to maintain firm contact with the rail under all load conditions. Thus, inasmuch as the bar takes loading engagement 65 with the head and base fillets of the rails, at least throughout its effective medial or rail end supporting portions, and therefore cannot move inward, abrasion is substantially eliminated and only little wear can 70 occur. However, it is to be expected that some looseness of the bar with respect to the rails will in time develop despite the elimination or the substantial elimination 75 of abrasion between the contacting surfaces of the bar and the rails, due to the pounding of car wheels passing over the joint.

Therefore, the invention also has in view the additional important purpose of so forming a joint bar of the character mentioned 40 that it is capable of being adjusted to take up any looseness which may develop in the joint, to which end the bar is formed medially for effective loading engagement with 45 the rails and, outwardly with respect to its medial loading portion, is laterally thinned so as normally to be disposed in spaced relation to the rails to enable inward adjustment or pressure of the bar when looseness 50 occurs at the medial portion thereof. More-

over, by reason of this construction and by tightening of the end joint bolts, the ends of the bar may be flexed inwardly with the result that the constant tendency of the bar to return to its normally straight condition 55 will cause the medial portion of the bar to be urged constantly inward into firm loading engagement with the rails.

In addition, it is an important purpose of the invention to provide a joint bar of the type mentioned which is capable of being economically rolled, and with these and other purposes in view, the invention consists in the novel construction and in the novel combination and arrangement of features as 60 65 will be hereinafter more fully described, illustrated in the accompanying drawings and defined in the appended claims.

In the drawings, wherein like characters of reference denote corresponding parts in 70 the different views:

Figure 1 is a detail side elevation of a rail joint including bars constructed in accordance with the present invention.

Figure 2 is a vertical cross section taken 75 on the line 2-2 of Figure 1.

Figure 3 is a vertical sectional view taken on the line 3-3 of Figure 1.

Figure 4 is a horizontal section on the line 4-4 of Figure 2.

Figure 5 is a vertical sectional view of a modified form of bar; and

Figure 6 is a horizontal cross sectional view taken on the line 6-6 of Figure 5.

Figure 7 is a detail cross sectional view 85 of a modified form of joint bar embodying the invention.

Referring to the drawings in detail, R, R' designate the meeting end portions of a pair of rails, and A a joint bar embodying the novel features of the present invention 90 and adapted for splicing the rails R, R' together.

As usual, each rail is inclusive of a head 10, a web 11, a base or flange 12 and head 95 and base fillets 13 and 14, respectively, located at the points where the web 11 merges into the head 10, and the base 12, respectively.

The joint bar A includes a head 15, a web 100

16 and a foot or base portion 17, but, as distinguished from general prior practice in the art of joint bar construction, and in accordance with the present invention, the 5 upper, inner corner of the head 15 of the bar is rounded, as indicated at 18, to provide a bearing element for loading engagement with the head fillet 13 of the rail, and, in addition, the heel 19 of the bar is 10 rounded, as indicated at 20, to provide a bearing element for loading engagement with the base fillet 14 of the rail. Moreover, the top and bottom faces 18^a and 20^a of the bar are extended outward toward the ends 15 at such angles relative to the rounded portions 18 and 20 of the head and heel of the bar, respectively, that the head 15 of the bar has clearance from the under face of the rail head 10 and the base or foot of 20 the bar has clearance from the upper face of the rail flange.

As a consequence of the foregoing construction the tendency of the bar A, when bolted in tightly and subjected to load, is 25 to move inward both at its head and at its base because of the loading engagement of the bar being solely with the head and base fillets of the rail, and the resultants of the lines of force being directed inward. Since, 30 however, the construction is such as to prevent inward movement of the bar, it follows that relative sliding movement between the contacting surfaces of the bar will be negligible, and as a result abrasion of such surfaces is substantially eliminated and 35 longevity of the joint is assured.

The construction described may be carried throughout the length of the bar or only 40 throughout a portion of the length thereof as will presently appear.

Referring to Figs. 1 to 5 inclusive, it may be pointed out that it has been established that a rail joint bar is subjected to maximum load and to maximum wear medially 45 thereof throughout a relatively short portion of its length extending inwardly from each rail end, and that the end portions of the bar sustain less load and are subjected to little or no wear. Accordingly, it is preferred to construct only the medial portion 50 of the present bar as heretofore described for continuous engagement with the head and base fillets of the rails, and to provide for clearance between the head and base 55 fillets of the rails and the rounded wearing elements 18 and 20 of the head and heel of the bar, respectively, from said medial portion to the ends of the bar. This is 60 illustrated in Figs. 2, 3 and 4 of the drawings wherein it will be observed that the medial portions of the head and heel of the bar have continuous contact with the head and base fillets of the rails, respectively, and that from said medial portions the head 65 and heel portions of the bar extend in

spaced relation to their related rail surfaces, this being preferably accomplished by thinning the end portions of the bar and by reducing the metal solely at the inner faces of these bar elements so that the out-to-out 70 of the joint is substantially uniform and maintained at the required distance.

Thus, by reason of the described construction, if looseness of the bar develops from loosening of the bolts or otherwise, the 75 clearance between the end portions of the bar and the rail surfaces permits the bar to be tightened inward to compensate for any wear or looseness that may have occurred along the medial contact portions of 80 the head and heel. Moreover, by reason of said clearances the end joint bolts may be tightened to such an extent as to flex or spring the ends of the bar inwardly whereby the resulting tendency of the bar to assume 85 its normal straight condition will result in an automatic take-up of any looseness which may develop in the joint.

This type of bar may be and preferably 90 is of uniform height throughout its length and its outer face preferably is flat and straight, as also is the inner face of its medial portion, the only variance from a uniform cross section being endwise of its medial portion where it is laterally thinned 95 to provide the clearances heretofore mentioned. Accordingly, said bar is readily capable of being produced by an economical rolling process.

Figures 5 and 6 of the drawing illustrate 100 the joint bar 21 preferably formed with a spring set, and having the head 22 and the heel 23 both formed for loading engagement 105 with the head and base fillets of the rails throughout the length of the joint. In this embodiment however, the web of the bar may be initially bowed outwardly, (as indicated by the dotted lines), to provide a substantially cambered outer bolting face 24 for the purpose of giving the bar sufficient resiliency or spring under pressure 110 from the joint bolts to maintain the bar in tight engagement with the head and base fillets of the rail. Thus any tendency to looseness or such wear as may occur may be 115 adequately compensated for by subsequent tightening of the joint bolts.

Figure 7 of the drawings illustrates a 120 joint bar 25, the same having the upper head fillet engaging surface 26 and the lower base fillet engaging portion 27, both adapted to contact throughout their length 125 with the head and base fillets of the rail. The body 25 of the bar is formed to provide sufficient resiliency or spring to cause the surfaces 26 and 27 to firmly engage the head and base fillets of the rail under the pressure 130 of the joint bolts. The body 25 of the bar is preferably made so that its outer surface has an initial camber to adequately provide

for taking up any looseness that may occur in the bar as a result of continued use. Thus, this form of the invention provides a bar having head and foot portions formed for loading engagement solely with the head and base fillets of the rail while the body thereof is responsive to bolt pressure for maintaining the bar in engagement with said fillets.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

We claim:

1. A rail joint including the rail, joint bolts, and a splice bar having head-clearance from the underside of the rail head and flange-clearance from the upper side of the rail flange and also having a loading engagement at the head and base fillets of the rail.

2. A rail joint bar having head and foot portions formed for loading engagement solely respectively with the head and base fillets of the rail.

3. A rail joint including the rail, the joint bolts, and a bar having head and foot portions formed for loading engagement solely respectively with the head and base fillets of the rail, and means responsive to the bolt pressure for maintaining the bar in engagement with said fillets.

4. A rail joint including the rail, joint bolts, and a splice bar having head and foot portions formed for loading engagement solely respectively with the head and base fillets of the rail, and means responsive to the bolts for maintaining the bar under spring pressure in engagement with said fillets.

5. A rail joint including the rail, the joint bolts, and a joint bar having loading engagement solely with the head and base fillets of the rail, and provided with a yielding portion responsive to the bolt pressure for maintaining the bar in operative engagement with the rail fillets.

6. A rail joint bar inclusive of a head formed for loading engagement with the head fillet of the rail and for clearance from the underside of the rail head, and a base formed for loading engagement with the base fillet of the rail and for clearance from the upper face of the rail flange.

7. A rail joint bar inclusive of a head formed medially for loading engagement with the head fillet of the rail and for clearance from the underside of the rail head, and a base formed medially for loading engagement with the base fillet of the rail and

for clearance from the upper face of the rail flange, the head and base of said bar outwardly of said medial portions thereof, respectively, being formed for complete clearance from the rail when said medial portions are engaged respectively, with the head and base fillets of the rail.

8. A rail joint bar inclusive of a medial portion and a laterally thinned portion extending from said medial portion to each end of the bar, said medial portion being inclusive of a head formed for loading engagement with the head fillet of the rail and for clearance from the underside of the rail head, and a base formed for loading engagement with the base fillet of the rail and for clearance from the upper face of the rail flange.

9. A rail joint bar of uniform height throughout its length inclusive of a medial portion and a laterally thinned portion extending from said medial portion to each end of the bar, said medial portion being inclusive of a head formed for loading engagement with the head fillet of the rail and for clearance from the underside of the rail head, and a base formed for loading engagement with the base fillet of the rail and for clearance from the upper face of the rail flange.

10. A rail joint bar inclusive of a head and a base each having a medial portion of uniform width and a portion of progressively decreasing width extending from said medial portion to each end of the bar, the medial portion of the head of the bar being formed for loading engagement with the head fillet of the rail and for clearance from the underside of the rail head, and the medial portion of the base of the bar being formed for loading engagement with the base fillet of the rail and for clearance from the upper face of the rail flange.

In testimony whereof we hereunto affix our signatures.
